TAPE CHUTE FOR MAIL TREATING
MACHINES

George S. Moore, Woodhaven, and Joseph T. Scheb, Brooklyn, N. Y., assignors to Commercial Controls Corporation, a corporation of Delaware

Application May 5, 1943, Serial No. 485,696

1 Claim. (Cl. 271—2.4)

1 This invention relates to a tape handling device for a mail treating machine or the like.

One of the objects of this invention is to provide a tape handling device for a mail treating machine which is sturdy in construction and dependable in operation. Another object is to provide a device of the above nature capable of efficiently feeding gummed paper tape or the like into position for the printing of postage thereon. Another object is to provide a device of the above character capable of continuous cyclic operation without interruption by reason of jamming of the tape. Another object is to provide a device of the above nature capable of dependably delivering successive lengths of tape into proper printing register relative to a postage printing mechanism or the like. Other objects will be in part apparent and in part pointed out hereinafter.

The invention accordingly consists in the features of construction, combinations of elements and arrangements of parts as will be exemplified in the structure to be hereinafter described, and the scope of the application of which will be indicated in the following claim.

In the drawing, wherein we have shown one form of our invention,

Figure 1 is a fragmentary partly schematic side elevation of our tape printing device in operative position relative to a printing mechanism, a portion of the device being broken away and shown in section; and,

Figure 2 is a fragmentary top plan view of the tape printing device.

Similar reference characters refer to similar parts throughout the views of the drawing.

Modern mail treating machines such as, for example, that shown in the copending application of Commodore D. Ryan and Edward P. Drake, Serial No. 369,570, filed December 11, 1940, are operable for the printing of postage on envelopes, cards and the like, or on gummed tape. Such a machine may, accordingly, be so set that the printing mechanism thereof is operable to print only on envelopes or cards and, under such setting, inoperative to print on tape, the tape handling mechanism either being disabled or moved out of operative position. Or, the machine may be set so that the printing device prints only on gummed tape, operation of the machine under this setting being such as to render it incapable of handling envelopes or cards. Thus, the machine is characterized by tape handling mechanism manually operable into and out of operative position.

2 Tape handling devices of this character, at least in most modern mail treating machines, usually include mechanisms which impart various movements of the tape, i. e. the leading end thereof, in order that the tape be set to proper printing register relative to the printing mechanism, so that the impression on the tape be uniformly spaced from the leading edge thereof, and this accordingly necessitates movement of this leading edge during one portion or another of the printing cycle. After the printing cycle is completed, the tape is usually cut by a cutting device which may be associated with the tape handling device and may have its gummed side moistened or left dry, as desired. This movement of the tape during the printing cycle may result in the tape's jamming within the tape chute of the tape handling device, which not only usually tears or irreparably wrinkles the printed end of the tape, but also disables the tape handling device to such an extent that it is often necessary for a trained service man to relieve the tape jam and repair any damages resulting therefrom. It is our belief that one of the causes underlying these tape jams is the dry mucilage on one side of the tape, i. e. the bottom side, as it passes through the tape handling device which produces a transverse arch in the tape as it leaves the roll, thus preventing the tape from passing through the tape handling device in flat form. Accordingly, if there is an obstruction in the way of the high point of the arch at the leading edge of the tape, this edge of the tape will catch and as following portions are fed they cannot pass through the machine if the leading edge is stopped, and the tape accordingly piles up in a mass within the tape chute. It is accordingly another object of this invention to provide a tape handling device which obviates these difficulties in a thoroughly practical and dependable manner.

Referring now to Figure 1, the tape handling device is generally indicated at 10, and is shown in operative position in relation to a printing device 12, illustratively the printing drum of a postage meter such as, for example, the meter shown in the above-mentioned application. As described in that application, the tape handling device is pivotable about the axis of a shaft 13 by manually operable mechanism not here shown, into and out of the operative position illustrated. When in operative position, the tape handling device 10 presents gummed tape 14 in printing position between a platen 15 mounted on shaft 13 and printing drum 12, so as to re-

ceive printing impressions from type 16 mounted on the printing drum. Drum 12 and platen 15 rotate counterclockwise and clockwise, respectively, and in timed relation, so that surface 17 of the platen and type 16 on the drum engage opposite sides of tape 14 and feed the tape through the tape feeding device until the type and platen disengage one another. At the end of the printing cycle, the printed end 14a of the tape is automatically cut off by a cutting device generally indicated at 18, so that this end of the tape may be removed and used as desired. A moistening device, generally indicated at 19, may be set as desired, either to moisten the cut off tape end 14a or not, depending on what use is to be made of the tape. The cut off device 18 and moistening device 19 are described in detail in the above-noted application.

The tape handling device 10 comprises a pair of side walls 20 and 21 (Figure 2) which are held in proper spaced relation by an arcuate plate 22 which is fastened to peripheral portions of the side plates by screws 23 and 24 (see Figure 1). Screws 23 (Figure 2) extend through side plates 20 and 21 and are threaded into tabs 22a formed on and extending from the forward edge of plate 22, this plate thus forming the bottom wall of a tape chute generally indicated at 25.

The top wall of tape chute 25 is formed by an arcuate plate 26 provided with depending flanges 27 (Figure 1) at its opposite longitudinal edges which respectively overlie side walls 20 and 21 (Figure 1) at the left-hand end and are held in place by screws 23 at about the mid portion. This top plate 26 is suitably spaced from bottom plate 22 and also from the upper edges of plates 20 and 21, so as to define with the bottom plate and side wall edges tape chute 25, which is of substantially uniform width throughout its extent.

The left-hand end of top plate 26, as shown in Figure 2, is cut away, i. e. is provided with a slot 28, and the right-hand end of this slot communicates with a wider opening 29 formed in that portion of the top plate which lies between the top of platen 15 and the bottom of printing drum 12 (Figure 1). This opening 29 in the top plate accordingly provides a space for the entry into the tape chute of type 16 on the printing drum, thus to enable the type to print on the tape lying within the chute. As the tape is printed, it is fed to the right through the chute, and out of the exit end thereof, the top plate 26 at this portion of the chute being provided with a tapered slot 30. The left-hand end of slot 30 preferably is of the same width as opening 29 in top plate 26 and at first tapers abruptly as at 30a and then gradually so that at the extreme right-hand end 30b slot 30 is relatively narrow, thus providing ample material at the right-hand or exit end of plate 26 for strength and rigidity. Underlying the extreme right-hand or exit end of plate 26 is a cut off plate 31 which is spaced from the top plate and accordingly forms therewith the exit end of chute 25, this cut off plate also being provided to cooperate with the cutting off device 18.

As noted hereinabove, it is often customary in tape handling devices of this character to move the tape into printing register during some portion of the printing cycle. In the tape handling device shown, the free end of the tape subsequent to the cutting off operation lies at 146 (Figure 1) and before another printing operation takes place, this end of the tape is retracted sufficient-

ly, i. e. moved to the left, so that the impression is made relatively near to end 14b of the tape, thus avoiding wastage of the tape. To effect this retraction, a lever 32 is provided, this lever being pivoted on a shaft 33 and having at its upper end a spring-biased shoe 34 adapted to engage tape 14. Lever 32 also carries a cam roller 35 which coacts with a cam 36 suitably connected to shaft 13 so that as the shaft and cam rotate roller 35 follows the cam contour and thus pivots lever 32 counterclockwise against the bias of a spring (not shown) so that shoe 34 on top of the lever retracts the free end 14b of the tape into proper position within the tape chute. The travel of shoe 34 is such that free end 14b of the tape is retracted to a point adjacent the right-hand end of opening 29, i. e. the left-hand end of slot 30 (as viewed in Figure 2) and 14b of the tape thus lying at the entrance to slot 30 when type 16 presses the tape against surface 17 of the platen 15.

As noted above, gummed tape, by reason of the shrinkage of the dry mucilage, has a tendency to curl in a direction away from the gummed side which, in this instance, would be the down side of the tape. This buckling tendency of the tape, i. e. its tendency to arch transversely often results in the top of the arch lying above the bottom side of the upper tape chute wall 26, so that if this wall were solid at the right-hand end, as viewed in Figure 2, rather than being provided with slot 30, the buckled or arched end of the tape would catch against the tape chute wall so that the following portions thereof as fed by the printing drum and platen would crumple, behind the leading edge of the tape, thus held stationary, and create a jam within the tape chute, accordingly destroying the imprint and perhaps damaging the tape mechanism. However, through the provision of slot 30, the arched free end or leading end of the tape is free to pass into the slot, and as the slot is tapered the arched end is gradually flattened so that when the free end of the tape emerges from the exit end of the chute between the cutter on cutting device 18 and cutting plate 31, the tape end is flat, or substantially so, and thus readily able to pass between the coacting cutting devices without becoming jammed therebetween.

Accordingly it will appear that we have provided a tape handling device that attains the several objects hereinabove set forth in a thoroughly practical and efficient manner.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

We claim:

In a tape handling device for a mail treating machine, in combination, a supporting structure comprising spaced side walls, means bridging said side walls and forming an arcuate tape chute having entrance and exit ends, means forming an opening transversely through said chute adjacent but spaced from said exit end, and a platen rotatably mounted between said side walls and having an operative surface adapted upon rotation of the platen to enter said chute adjacent said opening to feed tape through said opening and out of said exit end, the top surface of said chute having a slot formed therein between said entrance and said opening, the top

wall of said chute also having a tapered slot formed therein extending from said opening to said exit end, the width of said second-mentioned slot at said exit end being less than the width thereof at any other portion, said second-mentioned slot being unobstructed at its exit end.
